into the chamber or cylinder 28 ahead of the piston 24. Exhaust of this end of the cylinder also takes place through this passage and port.

Control means for tools of this character or for others which are generally similar is provided which in a number of respects materially improve tool operation. Thus, the present control mechanism embodies means by which the user need only initiate operation of the tool by a momentary act to produce a movement of the tool through one complete cycle of working stroke and return. The control mechanism is effective at the transition points between work and return strokes, to automatically reverse the pressure fluid connections and, at the end of the return stroke, to automatically reset itself to its initial or starting position. The control mechanism has a further feature in that it embodies means conveniently adjustable to a predetermined setting for automatically controlling the maximum force exerted upon the work.

Referring first to Fig. 1, the control mechanism is preferably disposed within the elongated boss 38 on the barrel end wall 31. The boss has a pair of parallel bores 37 and 38 therein in which, respectively, a throttle valve assembly 39 and a control valve assembly 40 (Fig. 3) are mounted. The throttle valve assembly embodies means for controlling the admission of pressure fluid to the device and under certain conditions for controlling the exhaust of expended pressure fluid therefrom. The control valve assembly embodies means for directing pressure fluid to drive the piston assembly in one direction or the other. It also embodies adjustable means for determining the end of the working stroke and thereupon automatically effecting a return of the assembly to its initial position to complete the cycle.

Referring to the structure of the throttle valve as shown in Fig. 3, the bore 37 has a throttle valve casing 41 secured therein as by a driven fit. The casing extends beyond one end of the boss for screw threaded engagement by a nipple 42 arranged for connection with a conduit (not shown) from a suitable source of pressure fluid. The casing has an internal bore 43, the central portion 44 of which is of restricted diameter to provide outwardly facing valve seats 45 and 46. The valve seat facing toward the nipple 42 (in this instance the seat 45) is normally closed by a throttle valve 47 urged thereagainst by a spring 48 bearing between the valve and the inner end of the nipple 42. The other valve seat 46 is closed by an exhaust valve 49 and the two valves are connected by a stem 50 so arranged that they have an alternating open and closed relationship.

The end of the throttle valve casing 41 opposite the pressure fluid inlet nipple 42 is spaced inwardly of the end of the boss 38 to provide a chamber 51 in which a hollow piston 52 is mounted with its closed end 53 opposed to a plug 54 screwed into the end of the boss 38. The piston 52 has an axial stem 55 for abutting engagement with the end face of the exhaust valve 49 so that, when pressure fluid is admitted to the chamber 51 between the piston and the plug 54 the piston will move to close the exhaust valve 49 and open the throttle valve 47 against the force exerted thereon by the spring 48.

The throttle valve housing 41 has a lateral passage 56 therein opening into the restricted central portion 44 of the internal bore 43 and leading to a port 57 formed in the boss 38 between the bores 37 and 38 therein. Seated in the bore 38 is a control valve casing 58 held in place by

right and left hand plugs 59 and 60, respectively (as shown in Fig. 3). The casing 58 has an intake port 61 for pressure fluid in communication with the port 57 and has longitudinally spaced exhaust ports 62, 63 registering with exhaust openings 64, 65 in the boss 38. One of the plugs, in this instance the plug 59, has an exhaust passage 66 therein leading from the internal space at one end of the valve casing 58. Further, the valve casing has a port 67 communicating with the port 29 which leads to the recess 30 in the end wall of the cylinder 28 behind the piston 24 and a longitudinally spaced port 68 (Fig. 1) communicating with the passage 34 leading to the side of the cylinder 28 ahead of the piston 24.

A control valve 69 of the spool type, slidably mounted in the casing 58, has annular pressure fluid conducting grooves 70, 71 therein arranged for constant communication respectively with the ports 67, 68. In the sliding movement of the valve, the annular grooves 70 and 71 are arranged alternately to place either the port 29 or passage 34 in communication with the pressure fluid inlet port 61 while connecting the other with exhaust through port 62 and opening 64 or port 63 and opening 65. The valve also has an intermediate position in which an annular rib 72 between the grooves 70 and 71 closes the intake port 61 and disposes the annular grooves 70 and 71 between and out of communication with both exhaust port (see Fig. 4).

The control valve has a deep recess 73 in one end thereof (in this instance the end which faces toward the plug 59) to receive one end of a spring 74. The other end of the spring bears against the flanged end of a stud 75 which extends axially through and has screw threaded engagement, as at 76, with the plug 59. The outer end of the stud carries a manipulating head 77. By employing screw threads of relatively fine pitch manipulation of the head 77 will effect adjustment of the tension of the spring 74 with a high degree of accuracy.

The spring normally urges the control valve toward the plug 60 and at this end of the valve the plug and the control valve casing form a chamber 78 (Fig. 5) for pressure fluid which acts on the adjacent end face of the control valve as a piston for shifting the control valve against the force of the spring 74. This end face of the control valve has a recess 79 therein to slidably receive what may be termed an auxiliary piston 80. The end of the auxiliary piston 80 within the control valve recess 79 has a peripheral groove and the inner end of the recess 79 is also grooved to provide a chamber 81 (Fig. 3) between the auxiliary piston and the control valve when the former is fully seated in the latter as shown in Fig. 1.

An annular groove 82 on the control valve communicates with the chamber 81 through a port 83. The groove 82 is arranged to communicate with a port 84 in the valve casing 58 (Figs. 2 and 3) in the starting position (see Fig. 3) and in the intermediate position (see Fig. 4) of the control valve. The port 84, as shown in Fig. 2 opens to a passage 85 leading to the recess 30 at the end of the cylinder 28. The chamber 78 is normally vented to atmosphere only when the control valve is in its starting position by such means as an external longitudinal groove 86 in the valve casing 58, opening through a port 87, into the chamber 78 and through a port 88 into the space 89 at the other end of the control valve. The port 89 is disposed adjacent to the end of

the control valve to be closed thereby as it moves from its starting position. The chamber 78 is also arranged for connection with line pressure as by way of a longitudinally extending groove 88 (Fig. 3) in the external wall of the control valve casing which leads from the intake port 81 to a port 91 opening into the chamber 78 a short distance from the end face of the plug 60. Preferably the relationship is such that the control valve opens port 91 just after it closes port 89.

Manually manipulable means is provided for effecting initial opening of the throttle valve 47 and closing of the exhaust valve 49. This means in the present instance acts through the throttle valve piston 52 and may be a mechanical instrumentality of suitable character such as a lever or solenoid actuated plunger. It is preferred, however, to utilize pressure fluid as the motive power for opening the throttle valve and, to this end, the plug 54 adjacent the piston 52 has an opening 92 therein to receive a coupling 93 for a conduit 94 connected with a suitable source of pressure fluid. Normally closed valve means, generally indicated at 95, having an operating lever 96 controls the admission of pressure fluid to the chamber 81 behind the piston 52. Once the throttle valve has been opened by the inward movement of the piston 52, it is so held by pressure fluid from the cylinder 28 admitted to the chamber 51 through an open passage 97 (Fig. 2) between the chamber and the cylinder recess 30.

In discussing the operation of the present device, it will be considered that the parts are in their initial or starting positions as shown in Figs. 1 and 3 and that the nipple 42 and conduit 94 are connected with suitable sources of pressure fluid. To initiate operation of the device the user momentarily opens the valve 95 by manipulation of the lever 96 to admit pressure fluid to the chamber 81 and cause piston 52 to open the throttle valve 47 and close exhaust valve 49. (This position of these parts is shown in Figs. 4 and 5). Pressure fluid thereupon flows to the ends of the cylinders 27 and 28 behind the pistons 23 and 24 therein through internal bores 43, 44, lateral passage 56, ports 57, 61, groove 70, ports 67 and 29 to the recess 30 at the end of cylinder 28 and thence through the bore 32 and the ports 33 in the piston rod 21 to the end of the cylinder 27. Pressure fluid thus admitted drives the pistons through their working stroke. At the same time, pressure fluid flows from the recess 30 through port 97 into the chamber 51 behind the piston 52 and exerts a holding force for maintaining the throttle valve open. This holding force is set up almost instantly after the throttle valve is opened so that more than momentary manipulation of the valve 95 by the operator is unnecessary.

As the piston moves through its working stroke the end of the cylinder 28 in advance of its piston 24 is connected to exhaust to atmosphere through port 35, passage 34, port 68, groove 71, exhaust port 62 and opening 64. During the working stroke of the pistons the chamber 81 between the inner end of the auxiliary piston 80 and the control valve is subjected to the force of the pressure fluid in the cylinder 28 through the recess 30, passage 85, port 84, groove 82 and port 83. However, the force thus exerted in the chamber 81 will, during the working stroke, be insufficient to overcome the force exerted on the control valve by the spring 74.

As the pistons reach the end of their working stroke as determined by the engagement of the

rivet sets with the work and the exertion of a compression force thereon, the working pressure of the fluid behind the pistons will increase to a value such that the force exerted thereby in the chamber 81 will overcome the force of the spring 74. Since the auxiliary piston 80 is seated against the plug 60 the control valve 69 will be shifted axially to its intermediate position (as shown in Fig. 4) where both of the annular grooves 70 and 71 are out of communication with the inlet pressure fluid port 61 and the exhaust passages 62, 64, and 63, 65. The initial movement of the control valve has, however, uncovered the port 91 to permit pressure fluid to flow from ports 57, 61 through groove 88 into the chamber 78 at the outer ends of the control valve and auxiliary piston whereby to continue the shifting movement of the control valve to its reversing position as shown in Fig. 5.

As is best shown in Figs. 2 and 4, the pressure responsive area in the chamber 81 (represented by the base of the recess 78) is substantially smaller than the comparable area of the chamber 78 (represented by the end face of the control valve 69). Consequently the force exerted to overcome the spring force even at its maximum, will be less than the effective force which will be exerted by the supply line pressure. The differential in the pressure responsive or piston areas therefore insures that the control valve will be shifted from its intermediate to its reversing positions with a quick snap action or movement regardless of such variables as fluctuations in supply line pressure, or the increase in the opposing force exerted by the spring as it is compressed or the adjustment of the device for heavy or light work.

Normally when live pressure is admitted to the chamber 78, the auxiliary piston 80 will move into the recess 78 to the position shown in Fig. 5. When it will do so depends on the fit of the parts and to some extent on the pressure in the chamber 81. If pressure fluid cannot leak from the chamber 81 because of an extremely close fit, the piston may not change its relationship to the control valve as shown in Fig. 4 as the control valve moves to its reversing position (Fig. 5). This will not affect the operation of the device. However, it is undesirable and usually impossible to obtain or preserve such a fit inasmuch as pressure fluid leaking from the chamber 81 to chamber 78 will assist in the movement of the control valve to its intermediate position, this added force being quite effective where the opposing force of the spring increases rapidly as it is compressed. Such leakage, together with leakage to the exhaust port 64 also vents the chamber 81 after its communication with the port 84 is cut off.

It will be noted (see Fig. 4) that the control valve during its movement into and past its intermediate position, closes the port 84 from the cylinder end substantially as the port 91 is opened to admit active pressure fluid to the chamber 78. There is, therefore, no indirect connection back to the cylinder end 28 by which cylinder pressure might be maintained or the active pressure connected to exhaust depending on the position of the control valve.

In the reversing position of the control valve, the end of the cylinder 28 behind the piston is connected to exhaust, the fluid trapped therein through the ports 29 and 67, groove 70, exhaust port 63 and opening 65. Pressure fluid is admitted to the end of the cylinder ahead of the piston

24 through port 81, groove 71, port 88, passage 84 and port 85.

At the transition point between the working and return strokes a holding pressure will be maintained in the chamber 51 to hold the throttle valve open against the force of the throttle valve spring 48 because the volume of the cylinder ends behind the pistons 23 and 24 is relatively large as compared to the restricted area of the exhaust passage therefrom which includes the ports 29, 61, 63 and 65 in series relation. The pressure drop in the exhaust end of the cylinder is therefore relatively slow during this period. Thereafter the return movement of the piston maintains sufficient pressure in the end of the cylinder being exhausted to hold the piston 52 advanced. The throttle valve will therefore be held open until the pistons return to their starting positions at which time the final escape of pressure fluid from behind the pistons 23, 24 with the resultant drop of pressure in chamber 51 allows the throttle valve to be closed by the force of its spring to complete one cycle.

Closing of the throttle valve and the concurrent opening of the exhaust valve 49 permits the pressure fluid trapped in the device by closing of the throttle valve to escape around the exhaust valve 49 through chamber 51 and to exhaust through a port 98 in the boss 86 (see Fig. 3). Hence, the pressure fluid in the chamber 78 at the end of the control valve and auxiliary piston 80 will exhaust allowing the spring 74 to return the control valve to its initial starting position. The cycle, it will be noted, will not repeat even though the user should fail to release the lever 86 after initiating operation since pressure fluid will pass to the chamber 78 after the control valve has reversed connections until the throttle valve has closed to allow the control valve spring 74 to function.

The return movement of the control valve opens the port 89 immediately after port 81 is closed to permit of complete exhaustion of the chamber 78 through port 87, groove 86, port 88, space 86 and exhaust passage 66. This exhaust connection is, incidentally, also effective to prevent a possible and undesirable accumulation of pressure fluid in the chamber 78 due to leakage or the like. The connection remains open until the port 89 is closed by the initial shift of the control valve to its intermediate position.

It will be understood that the working force exerted thereby can be controlled simply by adjusting the tension of the spring 74 that holds the control valve in its starting position. The shift of the control valve to its reversing position is determined by the increase of pressure in the cylinders 27, 28 at or near the end of the pistons' working stroke, which increase is determined directly by the opposing force imposed by the work. This increased pressure acts directly on the control valve itself, thus avoiding indirect control of the reversing movement thereof. Therefore, the transition point between the working and return strokes of the pistons may be accurately predetermined by adjustment of the tension exerted on the control valve by the spring 74. Since the increase of pressure in the piston cylinders is a function of the opposing force or resistance imposed on the tool at any point along the length of the working stroke, adjustment of the force of the spring 74 will be effective to determine the maximum force exerted on the work. Having predetermined by adjustment the cylinder pressure at which reversal is to take place,

increase in supply line pressure will not alter the operation of the device. Hence small rivets may be properly set and without difficulty from line pressure variations.

It will be evident from the foregoing that a novel control mechanism for a tool of this character has been provided which automatically produces one single complete cycle of operation after the operator has, by manipulation of the lever 86, opened the throttle valve. It requires only a momentary act to start the cycle after which the user may release the lever.

I claim as my invention:

1. A pressure fluid actuated tool having, in combination with a pressure fluid responsive driving piston, a piston cylinder having ports for admitting pressure fluid to the ends of said cylinder to move said piston through working and return strokes, a valve housing having a pressure fluid inlet, outlets communicating with said ports to the cylinder, and exhaust ports, a throttle valve and a control valve mounted in said housing in fluid pressure communication, said valves being of the pressure fluid responsive piston type, spring means urging said throttle valve to closed position, manually controlled means for opening said throttle valve, spring means adjustable to urge said control valve toward one limit of movement with a predetermined force opposed to the movement of said control valve by pressure fluid, an auxiliary piston defining a chamber with said control valve, said control valve having passages arranged at each of said limits to admit pressure fluid to a port for one end of said cylinder and connect the other port to exhaust, the pressure fluid being admitted to drive the piston through its working stroke when said control valve is in its spring urged limit position, said chamber being connected with the end of said cylinder under active pressure during the piston working stroke to shift said control valve initially when the pressure is sufficient to overcome the opposing spring force, the initial shift moving said valve to a position closing said passages, a passage opened by said initial shift to subject said control valve and auxiliary piston to pressure fluid to complete the movement of said control valve to its said opposite limit, means providing an open passage for subjecting said throttle valve to the pressure in the end of the cylinder under active pressure during the working stroke to hold the throttle valve open, said open passage and the exhaust passages from that end of the cylinder being restricted to insure maintenance of pressure during the transition period and return stroke of the piston sufficient to hold said throttle valve open until the return stroke is completed, and an exhaust valve closed and opened alternately when said throttle valve is opened and closed for exhausting the pressure fluid behind said throttle valve when closed.

2. A pressure fluid actuated tool having, in combination with a pressure fluid responsive driving piston, a piston cylinder having ports for admitting pressure fluid to the ends of said cylinder to move said piston through working and return strokes, a valve housing having a pressure fluid inlet, outlets communicating with said ports to the cylinder, and exhaust ports, a spring closed throttle valve in said housing, a control valve in said housing communicating with said throttle valve, said valves being of the pressure fluid responsive piston type, manually controlled means for opening said throttle valve, spring

means adjustable to urge said control valve toward one limit of movement with a predetermined force opposed to the movement of said control valve by pressure fluid, an auxiliary piston defining a chamber with said control valve, said control valve having passages arranged at each of its limits to admit pressure fluid alternately to one or the other of said ports and to connect the opposite port to exhaust, the spring urged position of said control valve establishing the connections for moving the piston through its working stroke, said chamber being connected with the cylinder end then under pressure to shift said control valve initially when the cylinder pressure is sufficient to overcome the opposing spring force, the initial shift being effective to stop pressure fluid flow to said cylinder and to subject said control valve to pressure fluid to complete its movement against the spring force thereon to establish the alternate connections, and means for exhausting pressure fluid from behind said control valve when the return stroke of said piston is completed.

3. A pressure fluid actuated tool having, in combination with a pressure fluid responsive driving piston, a piston cylinder having ports for admitting pressure fluid to the ends of said cylinder to move said piston through working and return strokes, a valve housing having a pressure fluid inlet, outlets communicating with said ports to the cylinder, and exhaust ports, a control valve mounted in said housing, spring means adjustable to urge said control valve toward one limit of movement with a predetermined force, said control valve and housing forming a pressure fluid cylinder at one end of said control valve for effecting movement thereof as a piston against the force of said spring to an opposite limit, an auxiliary piston in said last mentioned cylinder movable in the same direction as said control valve and providing an auxiliary chamber for pressure fluid therebetween, said control valve having passages arranged at each of said limits to admit pressure fluid alternately to one or the other of said ports and to connect the other of said ports to exhaust, said control valve at its spring urged limit being arranged to effect movement of said piston through its working stroke, passages for connecting said auxiliary cylinder with the end of said piston cylinder under active pressure fluid during said working stroke to shift said control valve initially when the cylinder pressure increases sufficiently to overcome the opposing spring force on said control valve, the initial shift positioning said control valve to close the pressure fluid passages and to open passages for admitting pressure fluid to the control valve cylinder to complete the movement of said control valve to its said opposite limit, valve means for controlling the flow of pressure fluid to said control valve, and means for closing said valve means and exhausting pressure fluid from said control valve cylinder at the end of one operative cycle.

4. A pressure fluid actuated tool having, in combination with a pressure fluid responsive driving piston, a piston cylinder, ports for admitting pressure fluid to the ends of said cylinder to move said piston through working and return strokes, a valve housing having a pressure fluid inlet, outlets communicating with said ports to the cylinder, and exhaust ports, a control valve mounted in said housing, spring means adjustable to urge said control valve toward one limit of movement with a predetermined force, said control valve

5 having passages arranged at each of said limits to admit pressure fluid alternately to one or the other of said ports and to connect the other of said ports to exhaust, said control valve at its spring urged limit being arranged to effect movement of said piston through its working strokes, means responsive to the pressure in the end of said piston cylinder under active pressure fluid during said working stroke for shifting said control valve initially when the pressure increase is sufficient to overcome the opposing spring force on said control valve, the initial shift positioning said control valve to close the pressure fluid passages and to open passages for subjecting the control valve to pressure fluid to complete the movement of said control valve to its said opposite limit, and valve means for controlling the flow of pressure fluid to and exhaust from said control valve.

20 5. In a pressure fluid actuated tool having a cylinder and piston actuator, means for controlling the flow of pressure fluid to and exhaust from opposite ends of said cylinder having, in combination, a valve housing having a manually controllable inlet for pressure fluid, passages leading to opposite ends of the cylinder, and exhaust ports, a control valve in said housing, adjustable means for urging said control valve to an initial position, pressure fluid responsive means for shifting said control valve to a reversing position, said control valve having passages adapted in each position to connect one end of said cylinder with pressure fluid and the opposite end with an exhaust port, and means responsive to the pressure in the cylinder end to which pressure fluid is admitted when said control valve is in its initial position for shifting said control valve to an intermediate position, said control valve in said intermediate position preventing pressure fluid flow to said cylinder and establishing a connection for pressure fluid to said responsive means for shifting said control valve to its reversing position.

45 6. In a pressure fluid actuated tool having a cylinder and piston actuator and passages for conducting and exhausting pressure fluid to and from the opposite ends of said cylinder, the combination of valve housing means having a pressure fluid inlet, a normally closed throttle valve in said housing means controlling the flow of pressure fluid, a control valve having spring means urging it to a starting position, passages effective when said control valve is in said starting position for connecting one end of said cylinder with the pressure fluid inlet, means responsive to an increase of pressure in said one end of the cylinder for overcoming the force of said spring means to shift said control valve to a reversing position, pressure fluid responsive means for holding said control valve in its reversing position, passages effective when said control valve is in said reversing position for connecting the opposite end of said cylinder with the pressure fluid inlet, exhaust passages from said one end effective during reverse movement of said piston to maintain pressure in said one end, means connected to be responsive to such maintained pressure for holding said throttle valve open, and an exhaust valve opened when said throttle valve is closed for releasing the holding pressure fluid on said control valve.

70 7. In a pressure fluid actuated tool having a cylinder and piston actuator and passages for conducting and exhausting pressure fluid to and from the opposite ends of said cylinder, the com-

11

bination of valve housing means having a pressure fluid inlet, a throttle valve in said housing means controlling the flow of pressure fluid, a control valve having spring means urging it to a starting position, passages effective when said control valve is in said starting position for connecting one end of said cylinder with the pressure fluid inlet and the opposite end thereof with exhaust, means responsive to an increase of pressure in said one end of the cylinder for overcoming the force of said spring means to shift said control valve to a reversing position, passages effective when said control valve is in said reversing position for connecting the opposite end of said cylinder with the pressure fluid inlet and said one end with exhaust, the exhaust passages from said one end being restricted to maintain pressure in said one end, a pressure fluid cylinder in said housing means, a piston in said cylinder responsive to pressure fluid to hold said throttle valve open, and an open passage between said one end and said last mentioned cylinder.

8. In a pressure fluid actuated tool having a cylinder and piston actuator and passages for conducting and exhausting pressure fluid to and from the opposite ends of said cylinder, the combination of valve housing means having a pressure fluid inlet, a throttle valve in said housing means controlling the flow of pressure fluid, a control valve in said housing means having spring means urging it to a starting position, passages effective when said control valve is in said starting position for connecting one end of said cylinder with the pressure fluid inlet and the opposite end thereof with exhaust, means responsive to an increase of pressure in said one end of the cylinder for overcoming the force of said spring means to shift said control valve to a reversing position, passages effective when said control valve is in said reversing position for connecting the opposite end of said cylinder with the pressure fluid inlet and said one end with exhaust, the exhaust passages from said one end being restricted to maintain pressure in said one end, and pressure fluid responsive means in open communication with said one end for holding said throttle valve open.

9. In a pressure fluid actuated tool having a cylinder and piston actuator and passages for conducting and exhausting pressure fluid to and from the opposite ends of said cylinder, the combination of a shiftable control valve having alternate positions for connecting one or the other of the ends of said cylinder with pressure fluid and the opposite end with exhaust to drive the piston through working and return strokes, a normally closed throttle valve controlling the flow of pressure fluid to said control valve, restricted exhaust passages from the end of said cylinder exhausted during the return stroke of said piston effective to maintain pressure in said end, and means responsive to such maintained pressure for holding said throttle valve open.

10. In a pressure fluid actuated tool having a cylinder and piston actuator, means for controlling the flow of pressure fluid to and exhaust from opposite ends of said cylinder having, in combination, a reversing control valve for directing pressure fluid first to one end and then to the opposite end of the cylinder, a throttle valve controlling the flow of pressure fluid to said control valve, means urging said throttle valve normally closed, a normally open exhaust valve for releasing pressure fluid from the control valve when the throttle valve is closed, said exhaust valve

5 being movable with said throttle valve to close when said throttle valve opens, manually operable means for opening said throttle valve, and means responsive to the pressure in the end of the cylinder to which pressure fluid is first admitted for holding said throttle valve open.

11. In a pressure fluid actuated tool having a cylinder and piston actuator, means for controlling the flow of pressure fluid to and exhaust from opposite ends of said cylinder having, in combination, a reversing control valve for directing pressure fluid first to one end and then to the opposite end of the cylinder, means urging said control valve to an initial position, a throttle valve controlling the flow of pressure fluid to said control valve, means urging said throttle valve normally closed, a normally open exhaust valve for releasing pressure fluid from the control valve when the throttle valve is closed and connected to move with said throttle valve to close when said throttle valve opens, manually operable means for opening said throttle valve, and means responsive to the pressure in the end of the cylinder to which pressure fluid is first admitted for holding said throttle valve open and for moving said control valve out of its initial to its reversing position.

12. In a pressure fluid actuated tool having a cylinder and piston actuator, control means for conducting and exhausting pressure fluid alternately to and from the opposite ends of said cylinder, the combination of a valve for controlling the flow of pressure fluid to said control means, and means responsive to the pressure in one end of said cylinder when pressure fluid is admitted thereto and also responsive to the pressure of the fluid being exhausted therefrom for holding said valve open.

13. In a pressure fluid actuated tool having a cylinder and piston actuator, control means for conducting and exhausting pressure fluid alternately to and from the opposite ends of said cylinder and having a normal position in which pressure fluid is directed to one end of said cylinder, the combination therewith of a valve controlling the flow of pressure fluid to said control means responsive to pressure in said one end of said cylinder for maintaining said valve open, and manipulable means for initially opening said valve momentarily at the start of the cycle to admit pressure fluid through the control means to said one end of said cylinder to actuate the pressure responsive means.

14. In a pressure fluid actuated tool having a cylinder and piston power source in which the piston is driven in opposite directions by pressure fluid admitted alternately to opposite ends of the cylinder, the combination therewith of control means for effecting the alternation of pressure fluid flow including a reversing valve yieldably urged to one position, said valve being pressure fluid responsive for movement to its reversing position and having differential pressure areas, and means for subjecting each of said areas to pressure fluid, the smaller of said areas being subjected to the lower pressure.

15. In a pressure fluid actuated tool having a cylinder and piston power source in which the piston is driven in opposite directions by pressure fluid admitted alternately to opposite ends of the cylinder, the combination therewith of control means for effecting the alternation of pressure fluid flow including a reversing valve yieldably urged to one position, said valve being pressure fluid responsive for movement to its re-

versing position and having differential pressure areas, means for subjecting the smaller of said areas to the pressure in one end of said cylinder, and means for subsequently subjecting the larger of said areas to a higher pressure.

16. In a pressure fluid actuated tool having a cylinder and piston power source in which the piston is driven in opposite directions by pressure fluid admitted alternately to opposite ends of the cylinder, the combination therewith of control means for effecting the alternation of pressure fluid flow including a reversing valve yieldably urged to one position and being pressure fluid responsive for movement to its reversing position, means for initially subjecting said valve to a pressure sufficient to move said valve against the force which yieldably urges it to said one position, and means for thereafter subjecting said valve to a higher pressure.

17. In a pressure fluid actuated tool, in combination, a cylinder and piston actuator, control means for effecting operation of said actuator in cycles each including forward and return strokes of said piston, said means including a control valve operable to direct pressure fluid alternately to opposite ends of said cylinder to effect such forward and return strokes of said piston, a throttle valve controlling the supply of pressure fluid to said control valve, means yieldably urging said throttle valve to a closed position, manually controlled means for shifting said throttle valve to an open position to initiate the forward movement of said piston, means operable in response to the completion of the forward stroke of said piston for shifting said control valve into a position to initiate the return stroke of said piston, means operative to hold said throttle valve in said open position independently of said manually controlled means, said throttle valve normally returning to the closed position under the influence of said yieldable means upon the completion of the return stroke of said piston, and means operative to hold said control valve in its shifted position and thereby prevent the initiation of another operating cycle until said throttle valve has been closed.

18. In a pressure fluid actuated tool, in combination, a cylinder and piston actuator, control means for effecting operation of said actuator in cycles each including forward and return strokes of said piston, said means including a control valve operable to direct pressure fluid alternately to opposite ends of said cylinder to effect such forward and return strokes of said piston, a throttle valve controlling the supply of pressure fluid to said control valve, means yieldably urging said throttle valve to a closed position, manually con-

trolled means for shifting said throttle valve to an open position to initiate the forward movement of said piston, and means providing a connection between said actuator and said throttle valve operative to hold said throttle valve in said open position independently of said manually controlled means until said piston has completed its forward and return strokes, said throttle valve being released for return to closed position as an incident to the completion of the return stroke of said piston.

19. In a pressure fluid actuated tool, in combination, a cylinder and piston actuator, cycling mechanism including a control valve operable to direct pressure fluid alternately to opposite ends of said cylinder to effect forward and return strokes of said piston, a throttle valve controlling the supply of pressure fluid to said control valve, means yieldably urging said throttle valve to a closed position, manually controlled means for shifting said throttle valve to an open position to initiate the forward movement of said piston, and means including a pressure fluid connection from said cylinder effective to hold said throttle valve in said open position independently of said manually controlled means through a single cycle of said actuator comprising forward and return strokes of said piston.

20. In a pressure fluid actuated tool, in combination, a cylinder and piston actuator, a control valve including a shiftable valve plunger yieldably urged to a position to direct pressure fluid into one end of said cylinder, said valve plunger being shifted automatically to interrupt the flow of pressure fluid to said cylinder upon a predetermined increase in the pressure of the fluid in said cylinder, an auxiliary plunger operable to further shift said valve plunger to a position for directing pressure fluid to the other end of said cylinder, and fluid passages controlled by said valve plunger for controlling the operation of said auxiliary plunger.

21. In a pressure fluid actuated tool, in combination, a cylinder and piston actuator, a control valve including a shiftable valve plunger yieldably urged to a position to direct pressure fluid into one end of said cylinder, means responsive to a predetermined increase in pressure in said one end of the cylinder for shifting said valve plunger to an intermediate position effective to interrupt the supply of pressure fluid to said cylinder, and an auxiliary plunger rendered operative upon the movement of said valve plunger to said intermediate position for further shifting said valve plunger to a position for directing pressure fluid to the opposite end of said cylinder.
